EDWIN S. LAMMERS, JR., OF ELYRIA, OHIO, ASSIGNOR TO WESTINGHOUSE ELECTRIC & MANUFACTURING COMPANY, A CORPORATION OF PENNSYLVANIA.

MOTOR-CONTROL SYSTEM.

1,417,750.

Specification of Letters Patent. Patented May 30, 1922.

Application filed May 28, 1919. Serial No. 300,391.

To all whom it may concern:

Be it known that I, EDWIN S. LAMMERS, Jr., a citizen of the United States, and a resident of Elyria, in the county of Lorain and 5 State of Ohio, have invented a new and useful Improvement in Motor-Control Systems, of which the following is a specification.

My invention relates to systems of control for motors operable singly or in tandem, 10 and particularly to systems involving the use of controllers operable at predetermined speeds to effect the acceleration of the motors with which they are associated.

Systems constructed in accordance with 15 my invention are adapted to be employed in connection with paper mills, rubber calenders and rolling mills where the tandem operation of motors is desirable.

Upon occurrence of predetermined abnormal 20 conditions, like voltage failure or overload, the motor becomes inoperative and cannot be again rendered operative until the controller returns to its initial position. Much valuable time may thus be lost, for the 25 controller continues to operate at the same predetermined speed that is suitable for accelerating purposes until it returns to the initial position.

An object of my invention is to provide an 30 accelerating system of the above-designated character, the controller of which shall return to its initial position at increased speed following the occurrence of abnormal conditions, so that the motor may be again 35 started without necessary delay.

A further object is to provide a control system for a plurality of motors whereby 40 they may be operated singly or together in any desired combination.

Other objects of my invention will appear 45 in the course of the following description and will be specifically pointed out in the appended claims.

In the accompanying drawings, Figure 1 50 is a diagrammatic view of circuits and apparatus embodying my invention and Fig. 2 is a schematic view of the circuits of the pilot motor.

A main electric motor 1, having an armature 2, an accelerating resistor 3 in series therewith, a series field-magnet winding 4 and a shunt field-magnet winding 5, is connected by a knife switch 6 to line conductors 7 and 8. A knife switch 9 is provided for

reversing the direction of current flow 55 through the shunt field-magnet winding 5. An adjustable resistor 10 and a field relay 11, having an actuating coil 12, are provided in circuit with the shunt field-magnet winding 5. The system comprises also an 60 overload relay 13 having actuating coils 14 and 15, a relay 16 having an actuating coil 17, and a relay 18 comprising contact members 19, 20 and 21, the first of which is normally closed and the other two of which are 65 normally open, and an actuating coil 22. A line switch 23, having normally open contact members 24 and 25 and a normally closed contact member 26, is provided with an actuating coil 27. A push-button switch 70 28 is adapted to start the motor, in the manner hereinafter described, and a plurality of push-button switches 29 and 30, which may be located in various desired positions, are adapted to stop the motor. 75

The main motor 1 is under the control of a pilot motor 31 having an armature 32, a resistor 33 in series therewith, a resistor 34 in shunt thereto and a shunt field-magnet winding 35. The resistors 33 and 34 may be 80 adjusted to vary the speed of the pilot motor 31, but, once adjusted, they are adapted to remain in the circuit of the pilot motor except under conditions described below. The pilot motor 31 operates, through gearing or other mechanism, a controller 135 having members 36 for controlling the main motor 1 and members 37 for controlling the pilot motor 31. The members 36 and 37 may be of any well-known drum-contact 85 type, in which case they may close circuits by bridging stationary contact members like those numbered 40, 51, 45 and 55, or they may be suitably designed cams of a cam controller 135. The controller 135 bridges contact members 40 and 45 in its "off" position and has a number of operative positions *a* to *i* inclusive. A knife switch 38 is adapted to establish the control circuits for the pilot motor 31 and may occupy either of two positions, in one of which it is adapted to control the pilot motor 31 singly and, in the other, to control it in tandem with other pilot motors in accordance with the position of a master switch 39. 95

Assuming that the knife switch 9 occupies its right-hand position, that the knife switches 6 and 38 occupy their upper posi- 100 105

tions, and that the controller 135 occupies its "off" position, a circuit may be traced from the line conductor 8, through the knife switch 6, the coil 14, the knife switch 9, the shunt field-magnet winding 5, contact members 40, which are bridged by a member 36 of the controller 135 to effect the short-circuiting of the resistor 10, the knife switch 9, the coils 12 and 15 and the knife switch 6, to the line conductor 7. The field relay 11 is thereby closed by its coil 12 and the shunt field-magnet winding 5 is strongly excited. If the knife switch 9 occupies its other position, to the left, the shunt field-magnet winding 5 will be excited by current flowing in the opposite direction.

Assuming that the controller 135 has been actuated to the position *a*, that the start push-button switch 28 is now actuated, a circuit may be traced from the line conductor 7, through the knife switch 38, the start push-button switch 28, the coil 17, and contact member 41, which are bridged by the controller 39 in the position *A*, by a conductor 42, to a junction point 43, and from this junction point 43, through the stop push-button switches 30 and 29, the field relay 11, the overload relay 13 and the knife switch 38, to the negative line conductor 8. The coil 17 becomes thereby energized by a circuit comprising the overload relay 13 to effect the closing of the relay 16. Upon the closing of the no-voltage relay 16, a circuit is established from the line conductor 7, through the switch 38, by a conductor 44, through a switch 16^a that is mechanically connected to the relay 16, the coil 17, the contact members 41 and so on, as before traced, to the junction point 43, which is connected to the line conductor 8. The coil 17 is thus maintained energized by a holding circuit comprising the mechanically connected switch 16^a. The start push-button switch 28 may now be released. A momentary actuation of the start push-button switch 28 is all that is necessary, for the relay 16 is of the small, quick-acting type.

The switch 16 establishes a circuit from the line conductor 7, through the knife switch 38, the conductor 44, the switch 16, contact members 45, which are bridged by a member 37, by a conductor 46 to a junction point 47. The junction point 47 is connected to the line conductor 8 through the windings 55 of the pilot motor 31. The circuit of the shunt field-magnet winding 35 may be traced from the junction point 47 through the winding 35 and the switch 38, directly to the line conductor 8. The circuit of the armature winding 32 extends from the junction point 47, by conductors 48 and 57, through the contact member 19, by a conductor 49 through the armature 32 and the switch 38, to the line conductor 8. The armature winding 32 and the shunt field-mag-

net winding 35 are thus energized to effect the operation of the pilot motor 31 at high speed until the controller 135 actuated thereby is moved to the first position *a*.

A circuit is then established from the line conductor 7, through the knife switch 38, by the conductor 44, through the switch 16^a, contact members 51, which are bridged by a member 37 in the position *a* by the conductor 52, through the coil 22 and the contact members 41, by the conductor 42 to the junction point 43, which is connected to the line conductor 8. The coil 22 will effect the closing of the switches 20 and 21 and the opening of the switch 19, which latter effects the insertion of the resistor 33 into the armature circuit, the switch 21 effecting the insertion into shunt with the armature of the resistor 34.

A new circuit for the armature 32 is established from the line conductor 7, through the switch 38, by the conductor 44, through the switch 16, and the contact members 45, by the conductors 46 and 48, through the resistor 33, by the conductor 49, through the armature 32 and the switch 38, to the line conductor 8. The resistor 33 is thereby inserted into circuit with the armature 32. The switch 21 establishes a circuit which extends from one side of armature 32 through conductor 49, switch 21, and resistor 34 to the other side of armature 32. The resistor 34 is thus inserted into circuit in parallel to the armature 32. By reason of the resistors 33 and 34 being respectively connected in series with, and in shunt to, the armature 32, the pilot motor 31 will be actuated at slow speed to effect the operation of the controller 135 at a predetermined slow speed. This result is thus obtained at the instant that the contact members 51 are bridged by a member 37 in position *A*.

A circuit is also established for the coil 27 from the conductor 44, which is connected to the line conductor 7, through the contact member 20, the coil 27 and the switch 38 to the line conductor 8. The switch 23 is thereupon closed by its coil 27. The motor circuit is then established from the line conductor 7, through the switch 6, the coil 15, the contact member 24, the armature 1, the series field-magnet winding 4, the resistor 3, the coil 14 and the switch 6, to the line conductor 8. It will be noted that the motor circuit is established by the switch 23, not by the controller 135. Further actuation of the controller 135 by the pilot motor 31 results in the short-circuiting of successive portions of the accelerating resistor until, in the position *i*, the resistor becomes entirely short-circuited. In the final position *i* of the controller 135, the contact members 40 are opened to effect the insertion of the resistor 10 into the circuit of the shunt field-magnet winding 5, thereby bringing the mo-

tor up to maximum speed. In the final position *i*, moreover, the circuit of the pilot motor 31 is broken at the contact members 45 so that the pilot motor 31 comes to rest 5 when the main motor 1 attains its full speed.

It will be noted that the contact members 40 control a portion only of the field resistor 10. This portion is of such value that severe 10 sparking at the brushes will not be caused 15 when the resistor 10 is inserted into the circuit of the motor field-magnet winding 5. This method of control nevertheless affords sufficient motor torque for acceleration purposes and is simple and requires no fluttering relays such as are commonly used. The 20 value of the starting torque that is required may be varied by adjustment, as indicated by the arrow 70. For example, if the arrow 70 is connected between the points 71 and 25 72, the contact members 40 have no effect. The contact members 40 are effective only when the arrow 70 is between the points 72 and 73.

In the position *b* of the controller 35, the 25 above-traced circuit of the coil 22 becomes broken at the contact members 51. A holding circuit is, however, first established, upon the closing of the switch 23, from the conductor 44, which is connected to the line 30 conductor 7, through the switch 16, and the contact member 25, by the conductor 52, the coil 22 and the contact members 41, by the conductor 42, to the junction point 43, which is connected to the line conductor 8.

35 The holding circuit for the coil 22 of the relay 18 is thus made through the contact members 25 of the switch 23. The switch 23 is usually a large contactor and is likely 40 in service, due to dirt and other causes, to close very sluggishly at times. For example, if the relay 18 formed its own holding circuit and the switch 23 closed very slowly, there would be danger of the switch 23 taking so long to close that the controller 135 45 would effect the short-circuiting of a large portion, if not the whole, of the resistor 3, and the motor 2 subjected to a high current peak in consequence, with subsequent damage to it and also to the circuit-breaker switch 23. Thus, by placing the holding circuit for the relay 18 under the control of the switch 23, this is prevented, for, if the switch 23 is not closed before the position *b* is reached, the circuit of the actuating coil 22 of the relay 18 will then be 50 broken and the switch 23 cannot then be closed until the controller 135 makes a complete revolution and the position *a* is again reached, when the relay 18 is once more closed and the circuit again established to the coil 27 of the switch 23. The pilot motor, therefore, when once started, will continue to rotate until the main motor 1 is 55 actually accelerated or until the stop button 60 and its corresponding circuit is open.

To stop the motor, one of the stop push-button switches 29 and 30 may be actuated to open the control circuits. The circuits of the coils 17 and 22 of the relays 16 and 18 become thereupon opened, whereupon the 70 circuit of the coil 27 becomes broken and the switch 23 drops open by gravity. The circuit of the pilot motor, which was broken at the contact members 45 in the final position *i* of the controller 35, becomes thereupon again closed by the contact member 26, the circuit extending from the line conductor 7, through the knife switch 38, by a conductor 54, through contact members 55, which are bridged by a member 37, by a conductor 56, through a resistor 74 of 80 relatively high value and the contact member 26, by the conductor 57, through the contact member 19, (the no-voltage relay 18 being now open) the armature 32, and 85 the switch 38 to the line conductor 8. The circuit of the shunt field-magnet winding 35 extends from the switch 26 which, as just traced, is connected to the line conductor 7, by the conductor 48, to the junction point 90 47, through the shunt field-magnet winding 35 and the switch 38, to the line conductor 8. The armature 32 is thus connected directly across the line conductors 7 and 8, free from the influence of the resistors 33 95 and 34, so that the controller 35 is actuated by the pilot motor 31 at high speed from the running position *i* to the initial position *a*.

The resistor 74, which is employed during the operation of the controller 135 from the 100 position *i* to the "off" position, is thus both in series with the field-magnet winding 35 and the armature 32 of the pilot motor 31. This resistor 74 is used merely to prevent drifting when moving the controller 135 105 from position *i* to the "off" position, for if the pilot motor were thrown directly across the line when stationary in position *i*, it would drift too far after the contact members 55 became opened, so that it would not 110 stop in the "off" position.

Upon failure of voltage during the normal accelerating operation, the relays 16 and 18 become opened by gravity irrespective of the 115 positions of the push-button switches 29 and 30. The same result takes place upon over-load conditions, when the overload relay 13 becomes opened to effect the de-energization of the coil 17 and the consequent opening of the relays 16 and 18. The above-traced 120 circuits for the pilot motor 31, which do not contain the resistors 33 and 34, become thereupon established, since the contact members 55 are bridged by the corresponding member 37 in the positions *b* to *e* of the controller 135, and the pilot motor 31 thereupon effects the operation of the controller 35 from whatever position it may happen to occupy, at the time, to the initial position *a*. The same result is attained if the stop push- 125 130

button switch 29 or 30 is actuated when the controller 135 occupies any of its positions, and the start push-button switch 28 is actuated immediately thereafter, the controller 135 proceeding thereupon to operate at high speed to accelerate the motor 1, and then returning to the "off" position. Under abnormal conditions, therefore, the controller 35 is actuated at high speed by the pilot motor 31 to its initial position, thereby effecting a saving of time in case it is desired to re-establish the main motor circuits immediately following the return of normal-circuit conditions.

15 It will be noted that the position *i* of the controller 135 is not the same as the "off" position. The two positions may, if desired, be made one, but in that event, an additional advantage accruing to the system as shown would be lost. In present commercial systems, a pair of switches like the switches 23, instead of only one, are employed, so that both sides of the line circuits may be opened, and difficulties due to 25 "grounds" thereby avoided. In the system of my invention, a single switch only is employed without the sacrifice of the above-referred-to advantage. This result is effected by advancing the controller 135 from the running position *i* to the "off" position, in which position the main motor circuits are open at all the desired points.

According to my invention, then, a pilot motor normally operates at a predetermined speed to effect the starting and the acceleration of a main motor. This is effected by providing, in circuit with the pilot motor, a pair of resistors, one in series with, and one in shunt to, the armature. Under abnormal conditions, however, the restraining influence of these resistors is removed and the pilot motor operates at increased speed, so as to return the controller to its initial position, in readiness for recommencing the 45 operation of the main motor.

The controller 39 is adapted to control not only the operation of the motor 1 but of any number of additional motors diagrammatically illustrated at 101, 201, 301 and 401, each of which is supplied with a control system, like that for controlling the motor 1, the stop and start push-button switches only of which are shown in the drawing.

The motors 1, 101, 201, 301 and 401 may be controlled in any desired combination, singly or in tandem, according to the position and the structure of the controller 39. For example, in the position A, not only is the motor 1 controlled as above described but also the motors 101 and 201 in tandem and the motors 301 and 401 in tandem, that is, the push-button switches for the motor 1 are adapted to control the motor 1 as above described; the push-button switches 45 of either the motor 101 or the motor 201 are

adapted to control both the motors 101 and 201 and the push-button switches of the motor 301 or the motor 401 are adapted to control both the motors 301 and 401.

In the position B of the controller 39, the 70 motor 1 is adapted to be controlled singly and all the other motors in tandem, that is, the push-button switches for the motor 1 are adapted to control that particular motor and any of the other push-button switches are 75 adapted to control all the remaining motors.

In position C, all the motors are controlled in tandem. In position D, the motors 1, 101, 201 and the motors 301 and 401 are controlled in separate groups. In position 80 E, the motors 1 and 101 are adapted to be controlled singly and the remaining motors in tandem. In position F, the motors 1, 101 and 201 may be controlled singly and the motors 301 and 401 in tandem. In the 85 final position G, all the motors are adapted to be separately controlled, each by its own push-button station.

Furthermore, if the switch 38 of any particular motor happens to be open, all the 90 motors that are controlled in tandem with the motor whose switch 38 is open will be rendered inoperative. If the push-button switch 38 of such a motor occupies its lower position, the remaining motors of the group 95 that are connected in tandem with that motor may all be operated but that motor rendered inoperative.

It is believed that this feature of the invention will be made clear from an inspection of the drawing without further description. The appended claims are designed to cover my invention in broad scope and it is desired that they be broadly construed except in so far as limitations may be specifically imposed therein.

I claim as my invention:

1. The combination with an electric motor, a controller therefor and a pilot motor operable at a predetermined speed to actuate said controller in one direction, of means for automatically effecting the operation of said motor in the opposite direction at a second and higher predetermined speed under predetermined conditions.

2. The combination with an electric motor, a source of energy therefor, and a controller therefor having a normal position, and normally operable from said position at a predetermined speed, of means for automatically returning said controller to said position at increased speed upon failure of power of said source.

3. The combination with an electric motor having a resistor associated therewith, a source of energy for said motor, and a controller operable at a predetermined speed to effect the short-circuit of said resistor, of a motor for actuating said controller and means for effecting the operation of said 125 130

motor to return said controller to normal position at an increased speed upon the occurrence of abnormal conditions.

4. The combination with an electric motor, 5 a switch for closing the circuit of said motor having an actuating coil, a relay for controlling the circuit of said coil and having an actuating coil, and a controller for effecting the acceleration of said motor, of means for 10 establishing the circuit of said relay coil in one position of said controller and means controlled by said switch for maintaining the circuit of said relay coil closed.

5. The combination with a main motor, a 15 controller therefor, and a pilot motor for operating said controller having armature and shunt field-magnet windings and resistors in series with, and in shunt to, said armature winding, of means for stopping 20 said pilot motor when said controller occupies a predetermined position in which said main motor operates at maximum speed, a third resistor, and means for connecting said third resistor in series with said armature and

shunt field-magnet windings during the operation of said controller from said predetermined position to said off position. 25

6. The combination with an electric motor, a controller therefor having an inoperative position and a pair of operative positions, 30 and a switch for closing the circuit of said motor when said controller occupies the first of said operative positions, of means for actuating said controller from the other of said operative positions to said inoperative 35 position upon the opening of said switch.

7. The combination with an electric motor and a controller for accelerating the same, of means for operating said controller at a predetermined speed during the acceleration 40 of said motor and at a second and higher predetermined speed upon the occurrence of abnormal current conditions to restore normal starting conditions.

In testimony whereof, I have hereunto sub- 45 scribed my name this 22nd day of May, 1919.

EDWIN S. LAMMERS, JR.
